UNITED STATES PATENT OFFICE.

CHRISTIAN G. KAMISKE, OF MILWAUKEE, WISCONSIN.

REFRIGERATING APPARATUS.

No. 822,054.

Specification of Letters Patent. Patented May 29, 1906.

Application filed September 3, 1904. Serial No. 223,314.

To all whom it may concern:

Be it known that I, CHRISTIAN G. KAMISKE, a citizen of the United States, and a resident of Milwaukee, in the county of Milwaukee and State of Wisconsin, have invented certain new and useful Improvements in Refrigerating Apparatus; and I do hereby declare that the following is a full, clear, and exact description thereof.

My invention has reference to refrigerating apparatus; and it consists in certain peculiarities of construction and combination of parts, as will be fully set forth hereinafter in connection with the accompanying drawings and subsequently claimed.

In the said drawings, Figure 1 is a vertical sectional view of my improved devices, taken on the plane indicated by the line 1 1 in Fig. 2. Fig. 2 is a like view taken on the plane indicated by the line 2 2 in Fig. 1. Fig. 3 is a horizontal sectional view taken on the plane indicated by the line 3 3 in Fig. 1.

Referring by numerals to the said drawings, 1 2 designate the ends, 3 the front, and 4 the back, of an inclosing case and 5 the top thereof, the said case being open at the bottom. 6 6 6 designate the members of a skeleton frame, projecting inwardly from the ends, front, and back of the said case to support the refrigerator proper, which latter is made of sheet metal; preferably galvanized iron, while the inclosing case is preferably of wood. The refrigerator 7 is double-walled, as shown at 8 8 8, at sides, ends, and bottom, except at its front, which has an opening 9 to give access to the interior thereof, this opening being guarded and closed by a sheet-metal door 10, hinged to one of the double-walled portions of said front, as best shown at 11 in Fig. 3. Each end of the said refrigerator 7 is provided with a series of strips 12 12, secured to the inner surface thereof, to support removable shelves 13 13. All portions of the interior of the described double walls are in communication, and a pipe 14 leads into this space between the walls to admit water thereto, so that said space may be kept filled therewith, there being a cock-controlled outlet-pipe 15, leading from the base of the refrigerator 7, to empty the said

space, if necessary, at any time; but in use the interior of the refrigerator is always surrounded by water at side, ends, and bottom, except at the front opening 9, closed by the door 10.

16 designates an ice-box, of sheet metal, supported on the top of the described double walls, as shown, which may be filled with ice when desired.

The refrigerator 7 does not come close to the inclosing case; but an air-space (indicated as 17 17) surrounds the said refrigerator 7 between it and the sides and ends, and there being communicating air-openings 18 18 through the top 5. There is also a water-gage 65 19 communicating with the water-space 8 to indicate the height of water in the latter at all times, and the front 3 of the inclosing case is provided with a door 20, hinged, as shown at 21, while the top 5 is hinged, as shown at 22.

The ice-box 16 may have separate cover, if desired.

The surrounding water keeps the contents of the refrigerator fresh and cool in all ordinary weather, and should the water become 75 too warm at any time it can be withdrawn through the outlet-pipe 15 and fresh water substituted, while, if necessary, the ice-box 16 can be filled with ice, although this is seldom necessary.

Having thus described my invention, what I claim as new, and desire to secure by Letters Patent, is—

The hereinbefore-described refrigerating apparatus, comprising an inclosing case of 85 wood or analogous material, open at the bottom and there provided with a skeleton supporting-frame and provided with a hinged door and top; a double-walled sheet-metal refrigerator resting on said frame, and having 90 a front opening covered by a protecting hinged door; and an open top; an ice-box resting on the top of the described double walls, the space between said walls being in communication, at front, back, ends, and 95 bottom; a water-inlet pipe communicating with the top of said double-wall space and a cock-controlled outlet-pipe communicating with the bottom of said space, and there being 100 communicating air-spaces surrounding

the sides and ends of said refrigerator, between it and the said inclosing case, and the hinged top having air-openings therethrough communicating with the said air-spaces surrounding said refrigerator.

5 In testimony that I claim the foregoing I have hereunto set my hand, at Milwaukee, in

the county of Milwaukee and State of Wisconsin, in the presence of two witnesses.

CHRISTIAN G. KAMISKE.
